UNITED STATES PATENT OFFICE.

ISAAC D. JOHNSON, OF KENNETT SQUARE, PENNSYLVANIA.

INVALID-BED.

SPECIFICATION forming part of Letters Patent No. 247,921, dated October 4, 1881.

Application filed August 22, 1881. (No model.)

To all whom it may concern:

Be it known that I, ISAAC D. JOHNSON, of Kennett Square, in the county of Chester and State of Pennsylvania, have invented a new and Improved Invalid-Bed; and I do hereby declare that the following is a full, clear, and exact description of the same, reference being had to the accompanying drawings, forming part of this specification, in which—

10 Figure 1 is a perspective view of the bed with the mattress removed. Fig. 2 is a vertical longitudinal section through the bed-frame. Fig. 3 is a rear view of the head of the bed. Fig. 4 is a detail, showing the means for fastening one end of the straps to the bed-rails to form the stretcher. Fig. 5 is a perspective view of the commode. Fig. 6 is a device for turning the patient from one side to the other.

15 My invention relates to certain improvements in invalid-beds. Said improvements consist, first, in the peculiar mechanism for raising a hinged head-section of the bed to bring the patient into a sitting posture or for lowering the same, as desired; secondly, in combining 20 with the said device counter-weights, that balance the weight of the patient's head and shoulders and enable the patient to adjust himself through a suitable cord and connections; thirdly, in means for locking and unlocking 25 the hinged head-section by the same movement that raises and lowers it; fourthly, in the combination of a stationary stretcher of canvas or straps with a subjacent mattress or bed made vertically adjustable beneath the same, to allow the bed to be removed from the patient to 30 cool his back, permit him to use the commode, receive injections, &c.; fifthly, in the means for regulating the tension of the stretcher; sixthly, in the peculiar arrangement of the 35 commode in relation to the mattress and the stretcher-frame; seventhly, in a supplemental opening with cover formed in the commode, to permit the patient to wipe himself after using the commode; eighthly, in the combination of a pulley, cord, and weight with the 40 stretcher, having a constant relation to the same, and an adjustable bed beneath the stretcher; ninthly, in a longitudinal rail located above the bed, to carry the cord that operates 45 the hinged head-section and to form a point 50 of attachment for a sling, by which the patient

is enabled to turn or partially shift himself in bed; and, tently, in means for turning the patient in bed, all as hereinafter more fully described.

55 In the drawings, A represents the main frame of the bed, which is in the nature of a complete rectangular frame independent of the head and foot boards B and C, which latter are screwed to the opposite ends of this rectangular frame when the bed is set up, or may be taken down and packed parallel with said frame in compact form for easy transportation.

60 Across the side bars of the main frame is distended the stretcher, which may be composed of a single sheet of canvas or a number of transverse strips, T, as shown. These strips are stretched transversely across the frame A, and are attached to the said frame at one side by bars a, Fig. 4, that are passed through a 65 hem or loop in the ends of the strap and then screwed to the frame, and on the other side have an adjustable connection with the rail, which permits the tension of the strips to be increased or lessened as desired. This adjustable connection consists (see Fig. 1) of a bar, 70 a', which is passed through the hem or loop on this end of the strips, which bar has a screw-threaded hole formed through the same, into which passes a vertical screw-stem, b, which 75 passes through a perforated lug, c, fixed to the side of the frame A, and terminates in a head swiveling beneath said lug. Now, by turning 80 this screw-stem it will be seen that the bars a' are drawn down and the strips drawn tighter 85 over the edge of the frame A.

To the main frame is hinged an ordinary 90 form of head-section, D, which forms a part of the stretcher and may fold inside the frame A or be raised to bring the patient into more or less of a sitting posture. To manipulate this 95 hinged head-section a rising and falling sash or frame, E, Figs. 2 and 3, is arranged to slide in guides just behind the head-board, and is connected to the hinged head-section by connecting-bars F, that are jointed to the outer portion of the head-section at one end and to the bottom of sliding sash or frame E at the other, which arrangement of parts gives a 100 constantly-increasing advantage in leverage as the head-section is raised. To said sash or frame is attached a cord, d, that passes over a pulley

at the top of the head-board and passes down into the range of reach of the patient or attendant.

To balance or nearly balance the weight of the patient's head and shoulders, so that he himself or his attendant may raise him by means of the cord, as described, without much effort, I place in suitable channels or guides in the posts at the head-board two weights, G G. These weights I attach to cords e e, that pass around pulleys at the top of the posts and are connected with the sliding frame, so that the tendency of the weights is to raise the frame and the hinged head-section of the bed.

In order to fix the inclination of the hinged head-section at any desired point, a notched bar, f, Fig. 3, is fixed to the back of the head-board, and the top rail, g, of the sliding frame is recessed to slide over it. Upon the top of this rail is a bolt, h, that is driven by a spiral spring, i, into the notches of bar f to lock the parts, and is withdrawn from said notches by a lever, j, pivoted in the top rail and passing through a slot in the bolt h. To this lever the cord d is attached, by which the frame is raised, the position of the lever j when the bolt is locked into the notches being such that a pull upon the cord d first withdraws the bolt from the notches of the bar f and then raises the frame and the hinged head-section, so that for unlocking and raising the head-section but one movement is necessary.

Just beneath the stretcher as sustained by the frame A is the mattress K, carried by a slatted frame, L. This mattress and frame are made to pass inside the main frame A and press up against and sustain the weight of the patient, or be lowered and leave the patient supported upon the stretcher. For giving the necessary movement to the mattress and frame the latter is suspended upon four cords, k k and l l, of which l l pass directly to a roller, M, while k k, which are at the foot of the mattress, pass first around pulleys m m and then extend in horizontal position to roller M. This roller is provided with a crank-handle, n, by which it is turned, and a ratchet-wheel and pawl, o, to hold it to any desired position. By winding or unwinding the cords upon this roller it will be seen that the mattress is raised or lowered as desired. When adjusted close up to the stretcher it sustains the weight of the patient and forms a comfortable bed. When, however, it is lowered it leaves the patient sustained upon the stretcher with a free circulation of air underneath, which permits his back to be cooled, allows him to use the commode, and permits him also to be washed or receive injections without being disturbed. By placing a pillow upon this mattress and then raising it against the body of the patient special support may be given to any part of the patient.

The commode consists of a box, N, extending crosswise the bed and sustained at its ends in grooves in the inner sides of the longitudinal rails of main frame A. About midway of

these rails are pivoted stops p, Fig. 2, which, when turned down, define the position to which the box is to be slid from its normal position at the head-board, stopping said box in a position immediately below a re-enforced opening in the stretcher beneath the seat of the patient. This box, when out of use, occupies a position close to and in front of the head-board, sliding in the grooves of the frame A beneath a stationary board, P, which acts as a cover to the box; or said box may, by turning the stops p up, be slid to the foot of the bed, where the grooves have an outlet at the bottom, through which the box may be entirely taken out. This box has an opening, r, Fig. 5, in its top, which registers with the re-enforced opening in the stretcher when the commode is being used, and has also an end door, t, Fig. 3, through which the chamber is inserted or removed. Beside the main hole r in the top of the box, there is also a smaller supplemental hole or opening, s, having a sliding cover, u, through which hole the patient may pass his hand to wipe himself without the necessity of raising himself from the box. In order to allow the commode to occupy a position at the head of the bed and still allow the mattress to be raised and lowered, the mattress is made shorter by an amount equal to the width of the box, and the supporting-frame for the mattress is made with a transverse opening at its end, (see Fig. 2,) adapted to pass up around the box whenever the mattress is raised.

With respect to a certain value which the sliding commode-box has in connection with the strips forming the stretcher and the adjustable mattress beneath, I would state that when the box is beneath the seat of the patient its hole may be provided with a cover and a cushion placed thereon. The stripped character of the stretcher then allows both feet of the patient to be placed between said strips and rest upon the mattress beneath, thus allowing his whole body to occupy a natural and easy sitting posture, as shown in dotted lines of Fig. 2.

R, Fig. 1, is a longitudinal rail or bar, which is sustained upon the top of the head and foot board, and carries the cord d. This rail has also another office, in that it supports a sling, v², above the patient, by taking hold of which the patient can secure a hold for turning, raising, or easing himself into a different position, which is particularly desirable in cases of inflammatory rheumatism.

S, Fig. 1, is a cord and weight passing over a pulley, v, fixed to the foot of the bed, which cord is designed to be attached to the foot or leg of the patient to produce a steady strain thereon in cases of fracture, where such strain is desirable to prevent shortening of the limb. I do not claim this pulley with cord and weight as broadly new for this purpose, but only in combination with the stretcher having a constant and unchanging relation to the pulley and the vertically-adjustable mattress beneath, where-

by the wants of the patient can be attended to without removing the tension from the fractured limb.

T², Fig. 2, is a detachable table, which has at one edge a pair of hooks that fit in eyes in the posts of the foot-board, while at its edge next to the patient it has folding legs, which, when turned into a vertical position, have their lower ends seated in sockets in the side rails 55 of the bed to sustain the table. When the table is not required for the meals of the patient or for reading, it can be entirely removed.

To turn the patient in bed from one side to the other, wide strips U, of canvas, oil-cloth, or other suitable material, may be attached to the stretcher-strips at the middle and left free at the ends, in which ends hand-holes are formed for pulling the patient over, or to which ends cords may be attached and carried over pulleys 20 on the longitudinal top rail for this purpose.

Instead of supporting the cord d on a longitudinal rail, R, as in Fig. 1, I may, if desired, employ a swinging bracket, B², as shown in Fig. 2.

Having thus described my invention, what I claim as new is—

1. The combination, with the hinged head-section of an invalid-bed, of a vertically-sliding frame arranged in guides back of the head-board, and rods jointed to the frame at the bottom and to the head-section at the top, substantially as and for the purpose described.

2. The combination, with the hinged head-section of an invalid-bed, of mechanism, substantially as described, for raising it, and one or more counter-weights to balance said head-section, as described.

3. The combination, with the hinged head-section of an invalid-bed, of a vertically-sliding frame connected to the head-section by jointed rods, a locking device arranged upon the vertically-sliding frame and adapted to engage with the rigid parts of the bedstead, and a cord connecting with the sliding frame through 40 said locking device, as described, whereby the unlocking of the frame and the adjustment of the same is effected by one and the same movement, as described.

4. In an invalid-bed, the combination, with 50 a stationary stretcher, of a subjacent vertically-adjustable mattress adapted to pass with-

in the frame of the stretcher and sustain the weight of the patient, or be dropped below the same, substantially as and for the purpose described.

5. The means for regulating the tension of the strips forming the stretcher, consisting of the combination, with said strips and the bed-rail, of bars arranged within the hem of said strips at the end, and having screw-holes 60 through the same, a headed screw-bolt passing through said bar, and also through a lug attached to the bed-rail, substantially as described.

6. The combination with the grooved side 65 rails of the stretcher-frame, the commode sliding vertically adjustable beneath the stretcher, sub- 60 ing horizontally therein, and the mattress made substantially as shown and described.

7. The stretcher-frame having transverse 70 strips across it and grooves in its inner sides, in combination with the commode-box made horizontally adjustable in said grooves, and the subjacent and vertically-adjustable mattress, 75 whereby the patient is allowed to occupy a natural sitting position with his feet below his seat, as described.

8. The commode having a circular opening in its top, with an opening at the side of the same, substantially as and for the purpose de- 80 scribed.

9. The combination of the pulley, weight, and cord at the foot of the bed, the stationary stretcher having a constant relation to said pulley and weight, and the subjacent vertically- 85 adjustable mattress, as and for the purpose described.

10. In an invalid-bed, the combination, with the foot and head board, of a longitudinal rail sustained upon the top of said head and foot 90 board, as and for the purpose described.

11. The combination, with an invalid-bed, of the strips U, for turning the patient, fastened at the middle to the bed and free at the ends, substantially as described.

The above specification of my invention signed by me this 17th day of August, 1881.

Corrections in Letters Patent No. 247,921.

It is hereby certified that in Letters Patent No. 247,921, granted October 4, 1881, to Isaac D. Johnson, for an improvement in "Invalid Beds," lines 66 and 67, on page 3, were inadvertently transposed by the printer in the printed specification attached to and forming a part of said Letters Patent; that the proper corrections have been made in the files and records of the Patent Office, and are hereby made in said Letters Patent.

Signed, countersigned, and sealed this 18th day of October, A. D. 1881.

[SEAL.]

A. BELL,
Acting Secretary of the Interior.
